UNITED STATES PATENT OFFICE.

GEORGE D. JORDAN, OF BASIC, VIRGINIA, ASSIGNOR, BY DIRECT AND MESNE ASSIGNMENTS, TO JORDAN CARBURETOR COMPANY, OF WILMINGTON, DELAWARE, A CORPORATION OF DELAWARE.

MANIFOLD FOR EXPLOSIVE-ENGINES.

1,277,424.

Specification of Letters Patent.

Patented Sept. 3, 1918.

Application filed April 6, 1914. Serial No. 830,025.

To all whom it may concern:

Be it known that I, GEORGE D. JORDAN, a citizen of the United States, residing at Basic, in the county of Augusta and State 5 of Virginia, have invented certain new and useful Improvements in Manifolds for Explosive-Engines; and I hereby declare that the following is a full, clear, and exact description thereof, reference being had to the 10 accompanying drawings, which form part of this specification.

This invention is a novel so-called "manifold" for use in connection with explosive engines of the multiple cylinder type; 15 through which manifold the fuel gases and the exploded gases are passed so that the explosive gases will be heated by the exploded gases, or waste products of combustion. The object of the invention is to provide a 20 manifold of novel and efficient construction in which the heat of the waste gases will be most advantageously utilized, and which manifold will be simple and neat looking.

In the drawings:

25 Figure 1 is a top plan view of the manifold applied to an ordinary four-cylinder engine.

Fig. 2 is a side view thereof.

Fig. 3 is a longitudinal section thereof.

30 Fig. 4 is an enlarged section on line 4-4 Fig. 3.

Fig. 5 is an enlarged section on line 5-5, Fig. 3.

35 Fig. 6 is a transverse section on line 6-6, Fig. 4.

The manifold shown in the accompanying drawings is particularly designed and adapted for use in connection with a four cylinder explosive engine, and is illustrated 40 in Fig. 1 as applied to a well known make of explosive engine.

As shown the manifold comprises a main hollow casing 1 which is preferably of cast metal, and is provided at one side with a 45 series of openings (1^a, 1^b, 1^c, 1^d, 1^e, 1^f) corresponding in number and position to the main inlet and outlet ports of the engine E shown as of the Ford type to which the manifold is to be attached; each opening being surrounded by a collar projecting laterally from the side of the casing and adapted to engage a corresponding socket or port of the engine; and said casing is gas-tightly connected to the engine by means of bolts 2

passing through sleeved openings 2^g in the 55 manifold and engaging suitably threaded holes in the engine casting as shown.

The outer ends of these bolts 2 preferably engage bridge pieces 2^h that rest upon facets (2^a, 2^b, 2^c, 2^d, 2^e, 2^f) corresponding in position and location to openings 1^a to 1^f; and the bridges are firmly clamped to the bolts by nuts 2ⁱ. The said facets are provided to facilitate machining the casing, and to provide uniform bearings for the bridges 2^h 65 thereagainst.

The casing 1 has a stem or nipple 1ⁿ on its lower side to which the carburetor (not shown) may be attached.

The openings 1^b and 1^e communicate with 70 the inlet ports of the engine; while the openings 1^a, 1^c, 1^d, 1^f, communicate with the exhaust ports. The openings 1^b, 1^e communicate with the opposite ends of an internal pipe or conduit 3 within the manifold, 75 which pipe is provided with a T 3^a that extends into the stem 1ⁿ and is adapted to connect with the fuel chamber of the carburetor, or other supply of explosive gases. It will be seen that the conduit 3 is practically separated from the walls of the casing 1 by an air space, which space is adapted to be filled with the exhaust gases when the engine is in operation, so that the fuel 80 gases are highly heated in passing through the manifold to the engine. The walls of nipple 1ⁿ are separated from the wall of T 3^a, by an air space 1°, so that hot gases may pass down through the space 1° and into the carburetor (the casing of which is connected to the nipple, but not shown) so as to heat the latter. The nipple 1ⁿ may be provided with a peripheral flange 1^p to which the carburetor can be conveniently connected.

90 The casing 1 is provided with a tubular extension 1^s which may be exteriorly threaded as at 1^t and is adapted to be connected to a suitable discharge pipe or muffler through which the hot exhaust gases finally 100 escape after traversing the manifold.

95 It will be seen that the explosive gas conduit is practically entirely surrounded by hot gases within the casing 1; that all the exhaust gases from the various cylinders 105 pass through this casing, and that while a portion thereof can be diverted through the passage 1° to heat the carburetor (not shown)

- the explosive gases coming from the carbureter, whether hot or cold, will be highly heated in traversing the conduit 3 before they escape through the openings 1^b, 1^c.
- 5 When the engine is operating this conduit 3 will be very highly heated, as it receives the hot exploded gases practically direct from the cylinder and while they are at their highest temperature.
- 10 The number and location of ports or openings in the manifold could of course be varied according to the number and location of the inlet and exhaust ports in the engine with which the manifold is to be used.
- 15 The manifold is preferably formed in one casting, with all the parts integral; it is very compact and neat and provides a very large extent of interior heating surface without the gases having to traverse any tortuous
- 20 passages. The conduit 3 being entirely incased within the hot exhaust chamber will retain its heat much longer when the engine is stopped, than it would if it was directly exposed to the atmosphere.
- 25 By passing the hot gases from the manifold into a carbureter directly connected to the nipple 1 the carbureter can also be highly heated with correspondingly increased efficiency in its operation.
- 30 What I claim is:
1. A manifold for explosive engines, comprising a hollow casing having openings at one side corresponding in number with the inlet and exhaust ports of the engine and communicating therewith, and laterally projecting collars surrounding said openings, a nipple depending from the lower side of the casing, and a discharge opening at one end of the casing; with a conduit within and
- 35 spaced from the walls of the casing so as to be substantially entirely surrounded by the hot gases therein and communicating at its ends with the openings in the casing that

connect with the inlet ports of the engine, and having a T extended into the nipple of 45 the casing and separated therefrom by an air space and adapted to be connected with the fuel gas supply.

2. A manifold for explosive engines, comprising a hollow casing having openings at 50 one side corresponding in number with the inlet and exhaust ports of the engine and communicating therewith; with a conduit within and spaced from the walls of the casing so as to be substantially entirely surrounded by the hot gases therein and communicating at its ends with the openings in 55 the casing that connect with the inlet ports of the engine, and having a T extended into the nipple of the casing and separated 60 therefrom by an air space.

3. A manifold for explosive engines, comprising a hollow casing having openings communicating with the inlet and exhaust ports of the engine, collars surrounding said 65 openings, a nipple depending from the lower side of the casing, and a discharge opening; with a fuel supply conduit within the casing leading from an inlet in the casing to the openings communicating with the 70 inlet ports of the engine, the walls of said conduit being spaced away from the walls of the casing so that the conduit is substantially entirely surrounded within the casing 75 by the hot gases therein, said conduit having its inlet extended into the nipple of the casing and adapted to be connected with a fuel gas supply.

In testimony that I claim the foregoing as my own, I affix my signature in presence of 80 two witnesses.

GEORGE D. JORDAN.
